UNITED STATES PATENT OFFICE.

WILLIAM C. STEWART, OF SWAMPCOTT, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

1,250,378.

Specification of Letters Patent. Patented Dec. 18, 1917.

Application filed March 30, 1914. Serial No. 828,258.

To all whom it may concern:

Be it known that I, WILLIAM C. STEWART, a subject of the King of Great Britain, residing at Swampscott, in the county of Essex and State of Massachusetts, have invented certain new and useful Improvements in Sole-Pressing Machines; and I do hereby declare the following to be a full, clear, and exact description of the invention, such as will enable others skilled in the art to which it appertains to make and use the same.

The invention relates to sole pressing machines, and is intended primarily for use in machines which are adapted to mold soles before they are incorporated in a shoe, although certain features of the invention may be used with advantage in other forms of sole pressing machines.

Sole molding machines as usually constructed are provided with two sets of molds which operate alternately, the vertically movable mold of one set moving toward the coöperating mold, while the vertically movable mold of the other set is moving away from the coöperating mold and into position to receive the sole. The mold actuating mechanism of these machines usually operates continuously during the molding of a lot of soles, the operator removing a molded sole and placing a new sole blank on each lower mold as it comes into its position of presentation. The molding pressure is therefore applied to the soles an instant only, and then relieved. In doing certain classes of work it is essential or desirable that the sole be subjected to molding pressure for at least a certain interval which may vary with the character of the stock operated on, or with the shape which is to be given to the sole. A dwell of the molds while the sole is under pressure may be secured by automatically stopping the machine when each set of molds is brought to sole pressing position. In such case, however, the length of the pressing interval depends on the judgment of the operator, who must re-start the machine after placing a new sole blank on the mold which is in position of presentation, and the length of the pressing interval will therefore necessarily vary. This also involves undesirable loss of time and reduction in the output of the machine, due to the fact that one set of molds must remain idle during the entire period

that the other set is applying pressure to the sole.

It is accordingly the object of the present invention to provide novel and improved mechanism which will operate to automatically secure a dwell of the molds in sole pressing position for at least a predetermined interval, and which will be free from the objections mentioned. To this end the invention contemplates the provision in a machine provided with sole pressing molds of mechanism for automatically disconnecting each set of molds from the mold actuating mechanism when the molds are in sole pressing position, and for reconnecting them with the actuating mechanism after a predetermined period. This construction insures at least a predetermined dwell of the molds in sole pressing position, secures a uniform dwell of predetermined length while the actuating mechanism is in continuous operation, and secures the desired dwell of the molds in sole pressing position without requiring a corresponding dwell in the position of presentation. The mechanism for disconnecting and reconnecting the actuating mechanism and molds may be of any suitable construction, and is preferably so constructed that the period during which the molds remain in sole pressing position may be varied to suit the character of the work being done.

In addition to the features outlined above, the invention also includes certain features of construction and combinations of parts which will be hereinafter described and referred to in the claims.

The features of the invention will be readily understood from an inspection of the accompanying drawings, and the following detailed description of the mechanism illustrated therein.

In the drawings, Figure 1 is a vertical sectional elevation showing so much of a twin sole molding machine as is necessary to illustrate the application of the present invention thereto; Fig. 2 is an elevation on a somewhat larger scale, showing the mechanism for disconnecting and reconnecting the molds with their actuating mechanism; Fig. 3 is a detail of part of the timing mechanism; Fig. 4 is a front elevation of the parts shown in Fig. 2; Fig. 5 is a sectional plan view of the parts shown in Fig. 4; Fig. 6 is

a detail sectional elevation showing a part of the devices for controlling the timing mechanism; Fig. 7 is a side elevation showing a part of the timing mechanism; Fig. 8 is a front elevation of the parts shown in Fig. 7; Fig. 9 is a detail plan view of devices for controlling the timing mechanism; and Fig. 10 is a vertical sectional view on line 10—10, Fig. 9.

10 In the drawings the invention is illustrated as embodied in a twin machine adapted for molding or shaping shoe soles, having the general construction of the machine illustrated in Patents Nos. 1,003,970 and 15 1,003,971, dated September 26, 1911. This machine is provided with two sets of molds, each comprising a fixed upper mold 2 and a coöperating vertically movable mold 4. The lower molds 4 are carried upon slides 6 20 mounted to reciprocate in vertically movable heads 8. Each head 8 is raised to bring the molds into sole pressing position, and lowered to bring the molds into position of clearance and presentation by a toggle comprising a link 10, the upper end of which is pivoted to the head and a link 12, the lower end of which is pivoted to the frame. Each mold carrying slide 6 is advanced as its supporting head 8 is lowered, and is retracted 25 as the head is raised, by a lever 14 connected with the slide and operated from the toggle link 10, as fully described in Patent No. 1,003,971 above referred to. The toggles are actuated to raise and lower the mold carrying heads by cranks 16 formed on the crank shaft 18 and connected with the toggles. The cranks 16, one only of which is shown, are arranged at an angle of 180° on the shaft 18, so that whenever one of the 30 lower molds is in its position of presentation, as indicated in dotted lines in Fig. 1, the other mold will be in sole pressing position, as indicated in full lines in this figure. One-half only of the twin machine has been 35 fully shown, since the other half is a duplication of that shown. The two upper molds, which are mounted one back of the other in Fig. 1, are sufficiently illustrated by the one which is shown in full lines, while one lower 40 mold is shown in full and the other indicated in dotted lines in this figure.

As thus far described, the machine is substantially the same in construction as the machine of the patents above referred to. 45 In embodying the preferred form of the invention in this machine, the connections between the actuating cranks and the mold raising and lowering toggles are so constructed that each toggle may be disconnected 50 from its actuating crank when the corresponding molds are in sole pressing position, and a timing mechanism is provided for reconnecting the toggle and crank after the crank has made a predetermined number 55 of revolutions or cycles. The devices for

connecting each crank and the corresponding toggle, and for disconnecting and reconnecting the toggle and crank, are the same in construction and mode of operation, and one set only of such devices have therefore been illustrated and will be described. As shown, the means for connecting the crank 16 with the toggle links 10 and 12 comprises a link formed in two sections 20 and 22. The section 20 engages the crank 16, and is mounted to slide on a rod 24 secured to the section 22. The section 22 is connected with the pivot pin 26 of the toggle, and its free end is adapted to butt against the free end of the section 20, as indicated in the drawings. The means for connecting or locking together the sections of the link consists of a latch lever comprising two arms 28 pivoted on the toggle pin 26, and provided at their rear ends with 70 hooks or recesses 30 adapted to engage pins 32 which project from the sides of the link section 20. The arms 28 of the latch lever are connected by a bolt 34 which overlies the link section 22, and are also connected at 75 their front ends by a bolt 36 and spacing sleeve 38. When the latch lever engages the pins 32, the sections of the link are connected or locked together so that they form in effect a rigid link connecting the toggle and crank so that the toggle is reciprocated by the crank. When the latch lever is swung into the position indicated in the drawings, the section 20 is free to slide back and forth on the rod 24 of the section 22 as the crank 100 16 revolves the toggle remaining in sole pressing position, while the crank revolves idly until again reconnected with the toggle by the engagement of the latch lever with the pins 32. When the latch lever is reengaged with the pins, the crank during its next revolution will actuate the toggle to move the lower mold into a position of presentation and return it to sole pressing position. As the crank brings the toggle and 105 mold into sole pressing position, the latch lever 28 is swung into the position indicated in the drawings to disconnect the toggle and crank by a cam 40 arranged to engage a roll 42 on the projecting end of the bolt 36. The toggle will now remain in sole pressing position against a stop screw 44 until the cam 40 is operated to release the latch lever and allow it to reengage the pins 32, and 110 thus reconnect the crank and toggle. The latch controlling cam 40 is formed on a lever pivoted on a stud 46 and held in normal position by toggle links 48 and 50, one of which is pivoted to the cam lever, and the other of which is pivoted on a fixed stud 52. 115 The links are connected by a pivot pin 54, and are provided with stop shoulders 56 for determining the straightening movement of the toggle. The toggle is broken to render the cam 40 inactive, and thus reconnect the 120 cam 40. The cam 40 is formed on a lever pivoted on a stud 46 and held in normal position by toggle links 48 and 50, one of which is pivoted to the cam lever, and the other of which is pivoted on a fixed stud 52. 125 The links are connected by a pivot pin 54, and are provided with stop shoulders 56 for determining the straightening movement of the toggle. The toggle is broken to render the cam 40 inactive, and thus reconnect the 130

crank and mold actuating toggle, through an arm 58 secured to a rock shaft 60, and carrying a roll 62 which engages a slot formed in a lug 64 which projects from the 5 toggle link 50. The rock shaft 60 is forced in a direction to straighten the toggle links 48 and 50 by a spring 65 connected to one arm of a lever 66 which is secured to the end of the rock shaft. The rock shaft is 10 rocked to break the cam retaining toggle by a timing mechanism which may be adjusted to actuate the shaft after the crank has made any desired number of revolutions or cycles. As shown, this timing mechanism 15 comprises an arm 68 carried by a ratchet wheel 70, and arranged to engage the lower end of the lever 66. The ratchet wheel 70 is mounted to turn freely upon a stud 72, and is provided on its rear face with a stop 20 lug 74 adapted to engage a fixed stop lug 76 and determine the normal or initial position of the ratchet wheel. The ratchet wheel is forced in a direction to engage the stop lug 74 with the stop 76 by a torsional spring 25 78, one end of which engages a fixed pin 80, and the other end of which engages a pin 82 projecting from the rear face of the ratchet wheel. The ratchet wheel is advanced against the tension of the spring 78 the distance of one tooth during each revolution of 30 the crank shaft of the machine by an actuating pawl 84 pivotally supported on one arm of a bell crank lever 86, the other arm of which carries a roll engaging a cam 88. The cam 88 is secured to a cam shaft 90 which is driven from the crank shaft and is given one revolution for each revolution of the crank shaft. The pawl 84 is forced toward 35 the ratchet wheel by a spring 92, and the tail 40 of the pawl is provided with a pin 94 arranged to engage a stop finger 96 on the lever 86 and limit the forward movement of the pawl, so that the pawl will disengage the ratchet wheel during each downward 45 stroke of the pawl carrying lever. The ratchet wheel is held against reverse rotation, after being advanced by the pawl 84, by a retaining pawl 98 held in engagement with the ratchet wheel by a spring 100. 50 The arm 68 is adjustably connected with the ratchet wheel so that it may be positioned to engage the lever 66 after the crank shaft has made any desired number of revolutions. As shown, the arm 68 is formed on a sleeve 55 102 mounted on the end of the stud 72, and is provided with a pin 104 adapted to engage any one of a series of holes 106 formed in the ratchet wheel. The arm is forced toward the ratchet wheel by a spring 108 60 which will yield to allow the arm and sleeve 102 to be drawn away from the ratchet wheel and to be turned into position to engage the pin 104 with any desired hole 106. The sleeve 102 may be provided with a scale 65 110 arranged to coöperate with a pointer 112 on the ratchet wheel in indicating the adjustment of the sleeve.

As shown, the arm 68 is so adjusted on the timing ratchet wheel that the mold will remain in sole pressing position during one 70 revolution of the crank shaft. Assuming that the ratchet wheel is in initial position, with the stop lug 74 in engagement with the stop 76, the ratchet wheel will be advanced one step, or into the position indicated in 75 the drawings, during the revolution of the crank which moves the molds from sole pressing position to positions of presentation, and then returns the molds to sole pressing position. As the crank brings the 80 toggle links 10 and 12 into the sole pressing position indicated in the drawings, the latch 28 is disengaged from the pins 32 by the cam 40, as above described, so that during the next revolution of the crank it will be disconnected from the toggle. During the next 85 revolution of the crank, the ratchet wheel 70 will be advanced one tooth from the position indicated in the drawings, and as the crank and link section 20 again come into the position indicated in the drawings, the arm 68 will actuate the lever 66 and thus rock the rock shaft 60 in a direction to break the cam supporting toggle links 48 and 50 and swing the latch controlling cam 40 out of active 90 position. This will release the latch lever 28, so that it may swing down and engage the pins 32, thus connecting the crank with the toggle links 10 and 12. During the next revolution of the crank, therefore, the molds 95 will be moved into the position of presentation, and returned to sole pressing position when the crank will be again disconnected from the toggle as before.

When the lever 66 is operated by the arm 100 68 as above described, a pin 114 projecting from the lever lifts the retaining pawl 98, so that the timing ratchet wheel and arm 68 may return to initial position. In order that the latch controlling cam 40 may remain in 105 inactive position when the ratchet wheel is thus returned, and releases the rock shaft 60, means is provided for retaining the lever 66 and rock shaft 60 in the position to which they are moved by the arm 68, until the crank 110 has carried the latch lever 28 away from the controlling cam 40. As shown, this means comprises a horizontal lever 116, the front end of which carries a block 118 arranged to engage the upper end of the lever 66 and 115 latch it in position. The latch block 118 normally rides against the side of the lever 66, and the block carrying lever 116 is forced in a direction to move the block in behind the upper end of the lever by a spring 120. 120 The latch lever 116 is operated to release the lever 66, and to allow the latch controlling cam 40 to return to normal active position by a slide 122, one end of which is arranged to engage the rear end of the lever 116, and 125 130

the other end of which is arranged to be engaged by a cam plate 124 on the toggle link 10. The slide 122 is forced forward by a spring 126, and its forward position is determined by a stop lug 128 arranged to engage the rear edge of the plate 130 which retains the slide in its guideway. The forward end of the slide 122 is provided with inclines 132 and 134 arranged to be engaged by the cam 124 and an incline 136 on the rear side of the toggle link 10. During the straightening of the toggle links 10 and 12, the incline 136 acts against the incline 132 and forces the slide 122 back so that the toggle link may pass idly by the end of the slide. As the toggle link comes into position against the stop screw 44, the slide 122 snaps forward into the position indicated in Fig. 9, so that the latch lever 116 is free to engage and retain the lever 66 as above described. When the toggle link 10 is reconnected to the crank, and is actuated to withdraw the molds from sole pressing position, the cam 124 forces back the slide 122, thus disengaging the latch lever 116 from the lever 66, so that the controlling cam 40 is returned to normal active position, ready to disconnect the crank from the toggle links 10 and 12 when the molds are returned to sole pressing position.

By proper adjustment of the timing arm 68 on the ratchet wheel 70, the molds may be caused to remain in sole pressing position during any desired number of cycles of the actuating crank shaft. While it will usually be desirable to similarly adjust the timing mechanism for each set of molds, so that the dwell of each set in sole pressing position will be the same, the timing mechanisms may if desired be adjusted so that one set of molds will dwell for a longer period than the other. Whatever the adjustment of the timing mechanisms, the molds will be moved from sole pressing position to a position of presentation, and returned to sole pressing position, during a single revolution of the crank shaft.

The crank shaft 18 may be driven through the proper gearing from a driving shaft 138, and the driving clutch may be controlled by a treadle 140 through starting and stopping mechanism similar to that illustrated and described in Patent No. 1,084,526, January 13, 1914. This controlling mechanism may be adjusted so that the crank shaft will rotate continuously so long as the operator keeps his foot on the treadle, or so that the crank shaft will be automatically stopped whenever one of the molds is brought to a position of presentation. In the latter case the clutch is held in engagement by a latch arm 141, the end of which carries a roll 142 adapted to engage the end of a sleeve 144 on the clutch shipping rod 146 when the rod is moved forward by the depression of

the treadle to engage the clutch. The latch arm 141 is connected to a sleeve 148 which carries two arms, one of which is indicated at 150. The upper end of each arm 150 is provided with a contact piece 152 arranged to be engaged by the end of the corresponding rod 20 when the link 22 is drawn back by the crank 16 in bringing the corresponding lower mold into a position of presentation. If the machine is to run continuously while the operator holds down the treadle, the sleeve 144 is adjusted on the rod 146 so that it remains under the roll 142 when the treadle is depressed. There is no lost time, due to the dwell of the molds in sole pressing position, in running the machine in either manner, since the mold which is moved into a position of presentation need remain in such position only long enough for the operator to remove the molded sole and place a new sole blank on the mold.

While it is preferred to employ the specific construction and arrangement of parts shown and described in embodying the invention in a twin sole molding machine, it will be understood that this construction and arrangement is not essential to the broader features of the invention, and may be varied or modified as found desirable or best suited to the construction of the machine in which the invention is to be embodied. It will also be understood that certain features of the invention are not confined in their application to twin machines, but may be embodied with advantage in other types of sole pressing machines.

Having explained the nature and object of the invention, and specifically described one form of machine in which it may be embodied, what is claimed is:

1. A sole pressing machine, having, in combination, sole pressing molds, actuating mechanism and connections between the actuating mechanism and molds for relatively moving the molds into positions of pressure and presentation, means for disconnecting the connections only when the molds are in a position of pressure, and a timing mechanism for controlling the reconnection of the actuating mechanism.

2. A sole pressing machine, having, in combination, sole pressing molds, actuating mechanism and connections for relatively moving the molds from a position of pressure to a position of presentation and back to a position of pressure during a cycle of the actuating mechanism, and means for disconnecting the actuating mechanism to leave the molds in sole pressing positions for a predetermined number of cycles of the actuating mechanism and for connecting it for a single cycle.

3. A sole pressing machine, having, in combination, two sets of molds, actuating mechanism therefor, mechanism for inde-

pendently disconnecting each set of molds from the actuating mechanism when in a position of pressure, and mechanism for controlling the reconnection of the disconnected 5 molds and actuating mechanism.

4. A sole pressing machine, having, in combination, two sets of sole pressing molds, actuating mechanism and connections for moving each set of molds into positions of 10 pressure and presentation, means for independently disconnecting the actuating mechanism from each set of molds only when that set is in a position of pressure, and mechanism for controlling the reconnection 15 of the actuating mechanism with each set of molds.

5. A sole pressing machine, having, in combination, sole pressing molds, an actuator moving to and from pressure-producing 20 position and connections for relatively moving the molds to produce pressure and clearance, and mechanism for disconnecting the actuator when in pressure producing position and for reconnecting it upon a subsequent 25 return to this position.

6. A sole pressing machine, having, in combination, two sets of sole pressing molds, reversely arranged actuators moving to and from pressure producing position and connections for relatively moving the molds of 30 each set to produce pressure and clearance, and mechanism for disconnecting each actuator from the corresponding molds when in pressure producing position and for reconnecting it with the molds upon a subsequent 35 return to this position.

7. A sole pressing machine, having, in combination, sole pressing molds, an actuator moving to and from pressure producing 40 position and connections for relatively moving the molds to produce pressure and clearance, mechanism for disconnecting the actuator when in pressure producing position, and a timing mechanism for reconnecting the actuator upon a subsequent return to pressure producing position adjustable 45 to vary the idle cycles of the actuator.

8. A sole pressing machine, having, in combination, sole pressing molds, a toggle 50 for relatively moving the molds to produce pressure and clearance, an actuator moving to and from pressure producing position and connections for operating the toggle, mechanism for breaking the connections 55 when the toggle is in pressure producing position and mechanism for timing the restoration of the connections.

9. A sole pressing machine, having, in combination, sole pressing molds, a toggle 60 for relatively moving the molds to produce pressure and clearance, a crank, a sectional

link connecting the crank and toggle, means for disconnecting the link sections when the toggle is in pressure producing position, and mechanism for timing the reconnection of 65 the link sections.

10. A sole pressing machine, having, in combination, sole pressing molds, a crank and connections between the crank and molds for relatively moving the molds to 70 produce pressure and clearance, mechanism for breaking the connections when the crank is in pressure producing position, and mechanism for timing the restoration of the connections. 75

11. A sole pressing machine, having, in combination, sole pressing molds, actuating mechanism and connections for relatively moving the molds to produce pressure and clearance, mechanism for disconnecting the 80 actuating mechanism when in pressure producing position, a timing ratchet wheel, an actuating pawl operated in time with the actuating mechanism, an arm adjustably connected with the ratchet wheel, and devices operated by the arm for controlling 85 the disconnecting mechanism.

12. A sole pressing machine, having, in combination, sole pressing molds, an actuator moving to and from pressure producing 90 position and connections for relatively moving the molds to produce pressure and clearance including a latch, mechanism for connecting and disconnecting the latch as the actuator moves into pressure producing 95 position, and a timing mechanism for controlling the re-connection of the latch.

13. A sole pressing machine, having, in combination, sole pressing molds, an actuator and connections for relatively moving 100 the molds to produce pressure and clearance including a latch for connecting and disconnecting the actuator and molds, a controlling cam for disengaging the latch as the actuator moves into pressure producing position, timing mechanism for rendering the controller cam inoperative, and connections for rendering the cam again operative after the actuator has moved the latch away. 105

14. A sole pressing machine having, in combination, two sets of sole pressing molds, a toggle for each set of molds, actuating mechanism for operating the toggles, mechanism for disconnecting each toggle from the actuating mechanism when the toggle is in 110 pressure producing position, and mechanism for timing the reconnection of the disconnected toggle. 115
